UNITED STATES PATENT OFFICE.

HARRY W. MITCHELL, OF CLEVELAND, OHIO, ASSIGNOR TO G. F. MITCHELL & SON, A PARTNERSHIP OF GEORGE F. MITCHELL, GEORGE R. MITCHELL, AND HARRY W. MITCHELL, OF CLEVELAND, OHIO.

WASHING MACHINE.

Application filed April 2, 1923. Serial No. 629,277.

This invention relates to a washing machine for washing clothes, fabrics and the like, and is designed particularly for household use, the washer disclosed herein being 5 of the type in which the clothes are washed in a rotating water tight drum in which the clothes and wash water are placed.

An object of the invention is to provide improved means within the drum for forcing air through the water and through the 10 clothes in the water during the rotation of the drum.

A further object is to provide perforated 15 partition members within the drum forming chambers adjacent the periphery of the drum in which air is trapped and carried beneath the surface of the liquid during the rotation of the drum, the partition members being readily removable to permit the interior of 20 the drum to be cleaned.

A further object is to provide an effectively sealed closure for the aperture in the drum through which the clothes are inserted and removed.

25 A further object is to provide improved reinforced heads for the drum and also to provide improved means for securing the supporting trunnions to the heads.

A further object is to provide a valve controlled 30 drain outlet for the drum together with conveniently accessible means for operating the valve.

A further object is to locate the drain outlet in a part of the drum where the clothes 35 within the drum cannot choke the drain outlet.

Other objects will be apparent from the following description and accompanying drawings.

40 Reference should be had to the accompanying drawings forming a part of this specification in which Fig. 1 is a transverse vertical section in the plane of the axis of the drum; Fig. 2 is an end elevation of the 45 drum; Fig. 3 is a top plan view of the drum; Fig. 4 is a fragmentary vertical section on an enlarged scale taken on line 4—4 of Fig. 1; Fig. 5 is a fragmentary plan view of the extensible perforated partition; Fig. 6 is a 50 fragmentary longitudinal section through one of the peripheral air trapping chambers; Figs. 7 and 8 are a plan and sectional view respectively of the trunnion carrying disks.

Referring to the accompanying drawings,

the washing drum 1 is horizontally disposed and is rotatably supported between upright portions 2 and 3 of the supporting frame and is driven by suitable driving mechanism 4 carried by the portion 2 of the frame. The driving mechanism is preferably of the automatic reversing type in which the drum is alternately driven a predetermined number of revolutions in each direction. The specific driving mechanism which I prefer to use for driving the drum is disclosed in my application Serial No. 629,278, filed April 2, 1923.

The drum 1 has a cylindrical sheet metal body 5 and sheet metal heads 6 and 7 secured to the ends of the cylindrical body. Each of the heads has a peripheral outturned flange 8 which fits within the cylindrical body 5. The body 5 has peripheral grooves adjacent its ends forming internal beads 9 against which the heads 6 and 7 engage. The edge portions of the sheet metal cylinder 5 are turned back over the peripheral flanges 8 of the heads 6 and 7 to unite the heads to the cylindrical body.

The heads 6 and 7 are sheet metal stampings formed with a raised central portion 10 from which the ribs 11 extend radially to adjacent the periphery of the heads. The reinforcing ribs 11 are relatively wide and deep adjacent the center of the head and taper toward the periphery thereof. Two crescent shaped depressions 12 positioned between radial ribs 11 with their ends adjacent the periphery of the head serve to further reinforce the head and also to provide arcuate ledges upon the inner sides of the head for a purpose which will be hereinafter set forth. A third crescent shaped depression 13 is provided at the end of one of the radial ribs 11 and serves the same purpose as the depressions 12.

Cup-shaped trunnion carrying disks 14 shown in detail in Figs. 7 and 8 are attached centrally to the heads 6 and 7. The disks 14 are provided with peripheral flanges 15 which have raised portions to fit over the ribs 11 and intermediate flat portions adapted to fit against the flat portions of the head between the ribs. The flange 15 of each disk is suitably secured to the head. Each cup-shaped disk 14 has a central aperture 16 through which the supporting trunnion extends, the trunnion 17 carried by the disk attached to the head 7 being a supporting

trunnion and the trunnion carried by the disk attached to the head 6 being a driving trunnion. The supporting trunnion 17 has a head 19 secured within the cup portion of the disk 14 attached to the head 7 and a stem 20 which extends through the aperture 16 of the disk and projects into a bearing 21 mounted on the supporting standard 3. The driving trunnion 18 has a head 22 secured within the cup portion of the disk attached to the head 6 and a hollow stem 23 extending through the central aperture of the disk. The hollow stem 23 has slots 24 extending inwardly from the end thereof to receive driving pins 25 on the end of a drive shaft 26 which extends into the hollow stem 23.

A series of segmental chambers 27 are provided adjacent the periphery of the drum upon the inside thereof by means of transversely curved partition members which extend from one end of the drum to the other and fit beneath the arcuate ledges formed by the depressions 12 and 13 in the head. Each of the partitions consists of a main 25 perforated plate 28 and a perforated extension plate 29 telescopically connected to the plate 28. The plates 28 and 29 are provided with central rows of perforations 30 and additional rows of perforations 32 adjacent the longitudinal edges thereof. The plate 28 has its edge portions rolled over to form hollow beads 33 which rest against the periphery of the drum. The extension plate 29 has similar edge heads 34 which are 30 adapted to fit slidably within the edge beads 33 of the main plate 28. The extension plate 29 fits within the end portion of the main partition plate 28 and is slidable longitudinally thereof. A pair of spring latch bars 35 are attached at one end to the underside of the plate 29 and have round upwardly extending studs 36 which have rounded ends and extend through apertures in the extension plate 29. The main partition plate 28 has apertures which register with the apertures in the plate 29 through which the studs 36 project when the plates are fully extended permitting the studs 36 to project through the apertures in both 35 plates and lock the plates in extended position. The partition plates 28 and 29 are so formed that they fit against the arcuate ledges 12 and 13 in the heads of the drum with their edge portions resting against the periphery of the drum. When the partition plates 28 and 29 are extended so that they are locked by the studs 36, the ends thereof will be beneath the ledges 12 or 13 in the heads and the partition member will be held rigidly in place. Whenever it is desired to remove these partition members as will be desirable for cleaning the interior of the drum, they can be removed by simply releasing the studs 36 by pushing them inwardly and sliding the extension plate 29

into the plate 28 until the partition member is released from the ledges on the heads.

In the operation of the machine the chambers 27 upon each revolution of the drum will move through the air space above the water in the drum and when in this position the water will drain out of the chamber and as the chambers 27 move through the liquid the air will be gradually displaced by water and forced through the openings 30 and 32 out into the body of liquid containing the clothes or fabrics being washed. The air streams so produced in the liquid serves to loosen up the fibers of the fabric being washed and greatly facilitates the cleansing action of the cleaning liquid. The purpose of the unperforated areas between the rows of openings 30 and 32 is to retard the entrance of water into the chambers 27 as the chambers are moving downwardly into the liquid and to retard the discharge of water from the chambers as the chambers are moving upwardly out of the liquid so that practically all of the air within the chambers will be discharged after the chambers are wholly submerged in the liquid and practically all of the water will be discharged after the chambers have been lifted out of the liquid, thus providing a more continuous discharge of air during the passage of the chambers through the liquid and in more continuous discharge of water during the passage of the chambers above the liquid.

An opening 37 is provided in the cylindrical body 5 of the drum between two of the air trapping chambers 27 and diametrically opposite another of the air trapping chambers. The sheet metal at the edge of the opening 37 is rolled back upon itself to provide a substantially cylindrical edge bead 38 surrounding the opening. The closure member 39 is formed with a marginal inwardly facing channel 40 which is adapted to fit over the edge bead 38 of the opening. The channel 40 has tapered walls providing a wedging engagement with the bead 38 and providing a space in the bottom of the channel above the bead 38 in which a suitable packing 41 may be placed. The closure member 39 is secured in place over the opening by means of suitable clamping bars 42.

A suitable drain fixture has a portion 43 forming an outlet passage attached to the cylindrical body 5 of the drum and communicating with the interior of the chamber 27 which is diametrically opposite the opening 37. The drain fixture has a valve chamber 44 just outside the end of the drum to which the drain passage 43 leads. The valve chamber 44 has an outlet controlled by a valve 45 which has a spring metal stem 46 which extends diametrically across the head and is slidably mounted in the disk 14 behind the head 19 of the supporting trunnion. The

valve 45 is normally held in closed position by means of a coiled spring 47 within the chamber 44. The outer end of the stem 46 is provided with a head 48 which has a shank 49 larger than the stem 46 and slidably fitting in a bracket 50 attached to the periphery of the drum. The bracket 50 has a keyhole slot 51 therein, the enlarged portion of which slidably receives the shank 49 of the head 48 and the narrow portion of which is adapted to receive the rod 46. To open the valve 45, the stem 46 is pulled upwardly until the shank 49 is clear of the bracket 50, whereupon the rod 46 will spring inwardly into the narrow portion of the slot 51, locking the valve 45 in open position. A small catch basin 52 is mounted on the standard 3 immediately beneath the end of the drum to which the drain fixture is attached and is provided with an outlet nipple 53 adapted to be connected to a suitable conduit for carrying away the liquid drained from the drum.

The drum operating mechanism preferably includes a device for stopping the rotation of the drum in such a manner that the drum will always be stopped with the opening 37 at the top and the drain fixture at the bottom directly over the catch basin 52. Such stop mechanism being shown in my pending application Serial No. 629,278, above referred to.

By reason of the fact that the drain fixture communicates with the interior of one of the air trapping chambers 27, the clothes or other fabric articles within the drum cannot interfere with the drainage of liquid from the drum since they cannot be drawn to the drain outlet.

Having described my invention, I claim—

1. A washing machine comprising a water tight drum adapted to receive the cleansing liquid and the articles to be cleansed, means for rotatably supporting said drum, and a plurality of inwardly bowed perforated partition members secured within the drum with the ends thereof engaging the ends of the drum and the longitudinal edges thereof engaging the periphery of the drum, said partition members comprising telescopically connected plates and means for retaining said partition members in extended position, the end walls of said drum being provided with retaining ledges engaging the inner sides of said partition members.

2. A washing machine comprising a rotatably supported water tight drum adapted to receive the cleansing liquid and the articles to be cleaned, partition members forming segmental chambers at the periphery of the drum, each of said partition members comprising a pair of telescopically connected perforated plates, a spring latch carried by one of said plates engageable with a perforation in the other plate to hold said

plates in extended position, the end walls of the drum being formed with ledges engageable with ends of the telescopic partition members to hold them in place.

3. A washing machine comprising a rotatably supported water tight drum adapted to receive the cleansing fluid and the articles to be cleansed, said drum having a cylindrical body and end walls formed of sheet metal, said end walls each having a plurality of arcuate depressions forming internal arcuate retaining ledges, the ledges at one end being aligned with corresponding ledges at the opposite end, and extensible arcuate partition members having their ends engaging said ledges, said partition members each comprising telescopically connected perforated plates.

4. In a washing machine having a water tight cylindrical drum, a partition member comprising a perforated curved plate having rolled over longitudinal edges, a second perforated curved plate having its end fitting within an end of the first plate and its longitudinal edge portions fitting within the rolled over edge of the first plate, and a pair of resilient strips secured to the inner side of the second plate, said strips having locking studs extending upwardly through perforations in the plate to which they are attached and engageable in perforations in the other plate.

5. In a washing machine a drum having a cylindrical body and sheet metal heads, each head being stamped to form a raised central portion and reinforcing ribs radiating from said central portion, and trunnion carrying disks secured to said heads, said disks being formed with a raised hub portion and a peripheral flange conforming to the ribbed surface of the head.

6. In a washing machine a drum having a cylindrical body and sheet metal heads, each head being stamped to form a raised central portion with ribs extending radially therefrom, said ribs being relatively wide adjacent the central portion and tapering toward their outer ends which lie adjacent the periphery of the heads, a trunnion carrying disk secured to each head, said disks each having a central cup-shaped recess, a peripheral flange and an aperture at the center of the recess, said flange being formed to fit over the ribs and conform to the surface of the head outside the central raised portion thereof, and a trunnion carried by each disk, said trunnions each having a base flange fitting within the cup shaped recess in the disk and secured to the disk and a stem projecting through the aperture in the disk.

In testimony whereof, I hereunto affix my signature.

HARRY W. MITCHELL.
